US0D1034076S

(12) **United States Design Patent** (10) **Patent No.:** **US D1,034,076 S**
(45) **Date of Patent:** **** Jul. 9, 2024**

(54) **COFFEE CUP**

(71) Applicant: **WUYI PENGSHENG INDUSTRIAL & TRADE CO., LTD.**, Jinhua (CN)

(72) Inventor: **Huaze Wong**, Jinhua (CN)

(**) Term: **15 Years**

(21) Appl. No.: **29/803,745**

(22) Filed: **Aug. 16, 2021**

(51) LOC (14) Cl. **07-01**

(52) U.S. Cl.

USPC **D7/510; D7/532**

(58) **Field of Classification Search**

(57) **CLAIM**

The ornamental design for a coffee cup, as shown and described.

DESCRIPTION

FIG. 1 is a perspective view thereof.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a bottom perspective view thereof.

The broken line portions of the coffee cup shown in FIGS. 7 and 8 form no part of the claimed design.

1 Claim, 8 Drawing Sheets
